MECHANICALLY CONTROLLED DISCHARGE
TUBE

George Fairburn Brett, London, England, assignor to Radio Corporation of America, a corporation of Delaware

Application September 21, 1938, Serial No. 230,916
In Great Britain October 14, 1937

4 Claims. (Cl. 250—27.5)

This invention relates to electron discharge devices for translating mechanical movements into electrical variations. It is known that an electron discharge device is capable of translating mechanical movements into electrical variations. Preferably a thermionic valve having a metal envelope is used. Special requirements, however, are that one end of the envelope should have a flexible diaphragm formation and that the anode should be attached to the inner surface thereof so that mechanical movement of the diaphragm occasions variation of the spacing of the anode from the rest of the electrode system of the valve and, therefore, changes the anode current. The main defect of this proposal is lack of sensitivity, a substantial mechanical movement of the diaphragm being required to effect a quite small change of anode current. The present invention seeks to overcome this defect and to provide electron discharge device mechano-electrical translators of improved sensitivity.

According to this invention an electron discharge device mechano-electrical translator comprises within a gas tight envelope, an electron gun system adapted to project a well defined jet or beam of electrons in a predetermined direction, a first collector electrode in the path of said jet or beam, and a second collector electrode which is movable with respect to said first collector electrode and is so arranged as to intercept the electron flow to said first collector electrode to an extent which varies with its position.

The invention is illustrated in the accompanying drawing which shows schematically one embodiment thereof.

Referring to the drawing, the translator device therein illustrated comprises within an evacuated envelope 1 an electron gun system constituted by a cathode 2, a control electrode 3, an accelerator anode 4 and a combined screen and suppressor electrode 5. The electrodes of this gun system are mounted in known manner on a footstep 1a formed in the re-entrant base of an envelope which is also formed with a projecting side tube 1b. The side tube is closed in a vacuum tight manner by a flexible metal diaphragm 6 which thus constitutes part of the envelope. The electron gun system may be of any form known per se in so-called "electron beam" valve practice; for example, as shown, the cathode 2 may be a rectilinear cathode situated behind a slot 3a in a plate-like control electrode 3 which is in turn behind a similarly slotted accelerator anode 4 with a slot 4a, the latter being itself behind a slotted plate-like screen and suppressor electrode 5 with a slot 5a. The slots 3a, 4a, 5a are aligned with one another and with the cathode, the slot 5a in the screen and suppressor electrode 5 being usually substantially wider than the slots 3a, 4a in the control and accelerator

anode electrodes 3, 4, respectively. With this arrangement a sharply defined ribbon sectioned beam of electrons as represented by the broken lines is projected in the direction of slot alignment. Situated in the path of the beam of electrons is a fixed collector electrode 7 carried by a support wire 7a fused through the top of the envelope, the arrangement of the electrode 7 and of the gun system being like that of a known electron beam valve. If the distance between the collector electrode 7 and the screen and suppressor electrode 5 is small (of the order of 2 to 4 mm.), the cross section of the electron beam may be as low at 0.2 mm. to 0.5 mm. and a quite high total beam current (of the order of 50 milliamperes) obtained for a cathode length and slot length of about 2 to 3 cm. Carried from the diaphragm 6 by a support wire 8a is a second collector electrode 8 which extends parallel to the fixed collector electrode 7 near thereto but between it and the gun. This electrode is edge on to the beam and is so positioned that normally, i. e. in its position of rest, the edge thereof furthest from the diaphragm 6 just grazes the edge of the electron beam or slightly overlaps said beam edge. If, therefore, the diaphragm 6 be bent inwards with respect to the envelope, the amount of electron current intercepted by the movable collector electrode 8 will increase and that to the fixed collector electrode 7 will, therefore, fall. In a device dimensioned as above set forth a movement of only 0.2 mm. of the movable electrode 8 may be caused to produce a fall of 50 m. a. in the current to the fixed collector electrode 7. If, therefore, 0.25 m. a. be regarded as an easily detectable current change, a mechanical movement of the movable electrode of only 10^{-4} cm. is easily detected.

Obviously current changes in opposite directions will occur simultaneously in the two collector electrode circuits in response to movements of the movable electrode and either or both of these current changes may be utilized. In general, however, it will probably be found most convenient to utilize only the current changes in the fixed collector electrode circuit.

Suitable applied potentials for a device constructed and dimensioned as above are (taking the cathode potential as zero):

50 Mean potential on control grid 3: zero or a few volts negative.
55 Potential on accelerator anode 4: 50 to 500 volts positive.
55 Potential on screen and suppressor electrode 5: zero.
55 Mean potential on movable collector electrode 8: 50 volts positive or more.
60 Mean potential on fixed collector electrode: 50 volts positive or more.

Devices in accordance with this invention are of wide application to practically all cases where mechano-electrical translation is required or useful. Examples of application are:

(1) *Altimeters and other pressure meters.*—For such application an aneroid, capsule could be used to move the diaphragm 6 by means of a lever or the said diaphragm could even form part of an aneroid capsule.

(2) *Microphones.*—Sound could be arranged to be incident direct upon the diaphragm 6 or a separate sound diaphragm mechanically coupled to the diaphragm 6 could be used.

(3) *Gramophone pick-ups.*—A needle adapted to run in a gramophone record could be used to drive the diaphragm 6. The whole device could be made quite small and light so as to be adapted to be fitted to a tone arm.

(4) *Magnetic pick-up for a telephone.*—In this case the diaphragm 6 could be made of magnetic material and the magnetically recorded tape passed in front of it so that the varying degrees of magnetization of the tape would produce corresponding slight movements of the diaphragm.

If desired mechanical biasing of the diaphragm to enable its normal position to be set where required may be provided for, e. g. by providing external means (not shown) for applying adjustable pressure to the diaphragm.

If means are provided for imparting mechanical movement to the second collector electrode otherwise than by mechanical coupling to the original source of mechanical movement, e. g., if the second collector is arranged to be moved by said source by means including a magnetic or an electrostatic or electro-dynamic movement communicating link, there is no need to provide the envelope with a flexible portion, for the movable collector electrode inside the envelope may be driven by means of the said link and an ordinary envelope employed.

I claim:

1. An electron discharge device having an envelope, a cathode, a beam focussing electrode, an accelerator electrode, and two target anodes, one of said target anodes being movable into and out of the path of the electron beam, and means including a flexible diaphragm sealed across an opening in said envelope and supporting said movable target anode for communicating movement thereto from outside the envelope.

2. An electron discharge tube having an envelope, a cathode, a control electrode, an orificed beam-focussing electrode, an orificed suppressor electrode, a target anode and a beam-intercepting anode, and means including a flexible support hermetically sealed across an opening in said envelope and having said intercepting anode mounted thereon for applying movements thereto from outside said envelope.

3. A device according to claim 2 wherein said cathode is linear and said orificed electrodes are constituted as means for forming the electron beam into a web toward the face of which an edge of said intercepting electrode is squarely presented.

4. A discharge tube comprising an envelope, a flexible diaphragm forming an hermetic seal across an opening in said envelope, electron beam producing and focusing means including a cathode, an accelerator electrode and another electrode, each of the two electrodes last mentioned having a single aperture of fixed dimensions through which to project a pencil of electrons, a target anode fixedly mounted in the path of the focused electron beam, and means including a shading electrode having an edge movably mounted in said path and supported by said flexible diaphragm and subject to displacement from without the tube for producing a variable degree of interception of electrons projected toward said target anode.

GEORGE FAIRBURN BRETT.
